UNITED STATES PATENT OFFICE.

JAMES E. VAN DEVENTER, OF ANDERSON, INDIANA, ASSIGNOR OF ONE-HALF TO
NELLIE VAN DEVENTER SMITH.

WORK-HOLDER FOR SEWING-MACHINES.

1,140,217.

Specification of Letters Patent. Patented May 18, 1915.

Application filed June 28, 1913. Serial No. 776,269.

To all whom it may concern:

Be it known that I, JAMES E. VAN DEVENTER, a citizen of the United States, residing at Anderson, in the county of Madison and State of Indiana, have invented a new and useful Work-Holder for Sewing-Machines, of which the following is a specification.

The object of my invention is to produce an improvement in that form of work holders for sewing machines shown in Patent No. 1,020,581, issued March 19, 1912, to Nellie Van Deventer Smith and myself.

The accompanying drawings illustrate my invention.

Figure 1 is a side elevation of a sewing machine with my improved work holder in work-holding position; Fig. 2 a perspective view of the bag and sustaining rods; Fig. 3 a side elevation of my improved form of clamp with the improved adjacent parts; and Fig. 4 a section on line 4—4 of Fig. 3.

In the drawings, 10 indicates the work-holding bag which is very similar to the bag in our prior patent, with a casing 11 at each end for the reception of one of the two sustaining rods 12, but here each casing 11 is provided with an eyelet 13 in the outer side of the casing near one end and with an eyelet 14 which is conveniently formed through both portions of the casing practically at that end, so that the rod 12 may be threaded through the main portion of the casing 11 and caused to emerge through the eyelet 13 and the eyelet 14 then threaded over the end of the rod 12, thus displacing a portion of the casing laterally from the rod 12 and leaving the rod uncovered for the space between the eyelets 13 and 14 for the reception of my improved clamp through which the rod 12 is threaded. This clamp is provided with a pair of eyes 15, 15 through which the rod 12 may be threaded and one

of these eyes carries a clamping screw 16 which may be driven into engagement with 45 rod 12 so as to hold it in any adjusted position. The main body of the clamp is U-shaped and comprises a bottom bar 17, an upright bar 18 and a top bar 19 which is parallel with the bottom bar 17, and threaded through the bottom bar 17 is a clamping screw 20 which, in coöperation with the top bar 19, may clamp the work table 21 of the sewing machine 22. By this arrangement, the sustaining rods 12 may be shifted 50 through the eyes 15 and held in any desired adjusted position, without loosening the clamp 17—18—19 from the work table, as was necessary in the structure shown in the above-mentioned patent. 60

I claim as my invention:

A work holder comprising a bag of flexible material having two opposite portions of its mouth formed into casings, each of said casings being provided near one end with a 65 pair of eyelets, a rod extending through each of said casings and through the eyelets and outside of the casing across the space between the two eyelets, a pair of clamps one for each rod, each clamp having a guide-way for the reception of a rod and fitting over the rod in the space between the two eyelets, a clamping screw for engaging said rod and holding the same in adjusted position in the guide-way, and a separate clamping screw independent of the rod and its clamping means, for clamping the clamp upon a work table. 70

In witness whereof, I, have hereunto set my hand at Indianapolis, Indiana, this 26th 80 day of June, A. D. one thousand nine hundred and thirteen.

JAMES E. VAN DEVENTER.

Witnesses:

GEORGE E. VAN DEVENTER,
G. B. SCHLEY.
